UNITED STATES PATENT OFFICE.

ROBERT L. KINTON, OF MEYERSDALE, AND AMOS F. HIBNER, OF CONNELLSVILLE, PENNSYLVANIA.

FIRE-BRICK MOLD.

Application filed December 19, 1922. Serial No. 607,891.

To all whom it may concern:

Be it known that ROBERT L. KINTON and AMOS F. HIBNER, citizens of the United States, residing at Meyersdale, in the county 5 of Somerset, and Connellsville, in the county of Fayette, respectively, and State of Pennsylvania, have invented certain new and useful Improvements in Fire-Brick Molds, of which the following is a specification.

10 This invention relates to improvements in molds and more especially to that class of molds which are employed in producing fire brick.

In the use of the ordinary mold which 15 comprises a rectangular body open at its top, the plastic material is poured into the mold and permitted to set and when the molded bricks are turned out onto the drying floor, this is done by overturning the mold so that 20 it will assume a position bottom uppermost, and then lifting the mold from the brick. However, it has been found that a very considerable percentage of the bricks are practically ruined through distortion in this 25 dumping operation for the reason that as the mold is turned over on one side, its side wall will momentarily flatly contact the drying floor, resulting in an impact which while slight is sufficient to impose a tamping 30 jar upon the brick within the mold causing its edge or side which is then uppermost to settle and become distorted. Therefore, the present invention has as its primary 35 object to provide a mold designed especially for use in the production of fire brick and which mold will be so constructed that in the operation of discharging the brick onto the drying floor, the mold will not be subjected to the impact or jar referred to above 40 and which is productive of the distorting tamping effect which produces an imperfect brick.

In the accompanying drawings:

Figure 1 is a perspective view of a fire 45 brick mold constructed in accordance with the present invention;

Figure 2 is a vertical transverse sectional view through the mold and the brick therein, the view illustrating in full and dotted lines the manner in which overturning of the mold to dump the brick is effected without a tamping jar being imposed upon the mold.

In the drawings, the mold is illustrated 55 as comprising a hollow rectangular body

open at its top, as is usual, and including opposite side walls 1, end walls 2, and a bottom 3, the lower edges of the side and end walls occupying, as usual, a common plane, and the bottom 3 being secured to the said lower edges of the end walls with its longitudinal edges terminating substantially in the plane of the inner sides of the side walls. In Figure 2 the numeral 4 indicates the brick which has been formed in the mold and which is to be discharged therefrom onto the drying floor.

As previously stated, in ordinary practice, when the mold is overturned, the outer face of one side wall thereof will momentarily strike flat against the drying floor thus imparting a jar or impact to the mold and creating a tamping effect upon the brick within the mold so that the edge of the brick which is then uppermost will settle more or less with the result that the brick when finally hardened and dried, will not be of true rectangular form but will be more or less distorted on one or two faces. The present invention resides in providing 75 rockers upon the outer face of one side wall of the mold which rockers are indicated in general by the numeral 5 and are adapted to insure against the impact referred to above and prevent any tamping of the brick 80 at the time the mold is overturned. These rockers are preferably two in number and are located adjacent the ends of the side wall upon which they are formed or provided and are preferably in the form of 85 bosses which have rounded tread surfaces 6. The tread surfaces 6 describe a substantially cycloidal curve. That is to say, the surface of each rocker, from the juncture of the outer side and lower edge faces of the 90 side wall 1 of the mold body upon which it is formed or provided, is curved gradually in an outward direction and toward the opposite edge face of said wall, as indicated by the numeral 7, being, however, more or 95 less abruptly curved inwardly to merge with the said upper edge face of the wall 1, from a point nearly midway the length of the rocker, as indicated by the numeral 8, and as clearly shown in the drawings. 100

Referring now to Figure 2 of the drawings it will be observed that when the mold is tilted to the dotted line position indicated by the reference letter A in said figure, that edge of the bottom 3 which is next ad- 105

ja⁵cent the wall 1 of the mold upon which the rockers are provided, will rest upon the drying floor as will also the lower edge of the outer face of the said side wall 1. At this moment, however, the inner or rear end of the tread 6 of each rocker will likewise contact the floor surface, and when the mold is further overturned to assume first the full line position shown in Figure 2 and then the 10 dotted line position indicated by the reference letter B, the treads of the rockers will ride upon the floor surface, maintaining the outer side of the side wall 1 upon which the rockers are provided, clear of the drying 15 floor so that the overturning operation is effected without the usual jar and incident distortion of the brick.

Having thus described the invention, what is claimed as new is:

- 20 1. A mold comprising a bottom and encompassing walls and entirely open at its top to permit of unrestricted discharge of the molded product when the mold is completely inverted, the mold being provided upon 25 one of its said walls with spaced rockers to engage a surface upon which the mold is to be overturned, the said rockers having arcuate tread surfaces, the tread surface of each rocker, at one end, terminating substantially 30 at the normally lower edge of the wall upon which the rocker is provided and at its other end merging substantially with the normally upper edge of said wall, the said tread surface of the rocker throughout its length 35 describing a substantially cycloidal curve the higher portion of which is nearer the open top than the bottom of the mold.
2. A mold comprising a bottom and encompassing walls and entirely open at its 40 top to permit of unrestricted discharge of the molded product when the mold is completely inverted, the mold being provided

upon one of its said walls with spaced rockers to engage a surface upon which the mold is to be overturned, the said rockers having 45 arcuate tread surfaces, the tread surface of each rocker, at one end, terminating substantially at the normally lower edge of the wall upon which the rocker is provided and at its other end merging substantially with 50 the normally upper edge of said wall, the said tread surface of the rocker throughout its length describing a substantially cycloidal curve and which curve is of gradually increasing abruptness from the first-mentioned to the last-mentioned end of the tread surface.

3. A mold comprising a bottom and encompassing walls and entirely open at its top to permit of unrestricted discharge of 60 the molded product when the mold is completely inverted, the mold being provided upon one of its said walls with spaced rockers to engage a surface upon which the mold is to be overturned, the said rockers having 65 arcuate tread surfaces, the tread surface of each rocker, at one end, terminating substantially at the normally lower edge of the wall upon which the rocker is provided and at its other end merging substantially with 70 the normally upper edge of said wall, the plane occupied by the said upper edge of the said wall being tangent to the curve of the said upper portion of the rocker, the tread surface of the rocker throughout its length 75 describing a substantially cycloidal curve which is of gradually increasing abruptness from the first mentioned to the last mentioned end of the tread surface.

In testimony whereof we affix our signatures.

ROBERT L. KINTON. [L.S.]
AMOS F. HIBNER. [L.S.]
